ATTORNEYS.

UNITED STATES PATENT OFFICE.

JONATHAN E. PIERCE, OF DEMING'S BRIDGE, TEXAS.

WIRE-FENCE STRETCHER AND SPLICER.

SPECIFICATION forming part of Letters Patent No. 295,801, dated March 25, 1884.

Application filed September 29, 1883. (No model.)

To all whom it may concern:

Be it known that I, JONATHAN E. PIERCE, a citizen of the United States, residing at Deming's Bridge, in the county of Matagorda 5 and State of Texas, have invented a new and useful Improvement in Wire-Fence Stretchers and Splicers, of which the following is a specification, reference being had to the accompanying drawings, of which it forms a part.

10 My invention relates to improvements in wire-fence stretchers and splicers; and it consists in the peculiar construction and arrangement of the parts, as hereinafter more fully set forth, and pointed out in the claims.

15 Figure 1 is a perspective view of my invention. Fig. 2 is a vertical section on line $x x$ of Figs. 1. Fig. 3 is a side elevation, part in section; and Figs. 4 and 5 are detail sectional views.

20 Referring to the drawings, a represents an open box, in the ends of which is journaled a screw, b , one end of which is prolonged, and provided with a vertical bevel-pinion, c , gearing with a bevel-pinion, d , journaled in a lug, 25 e , situated at one end of the box a , and forming a continuation of one side of it. The outer end of the axle e of the bevel-pinion d is provided with a crank, f , by means of which a rotary motion is imparted to the screw by 30 means of the pinions $c d$.

25 $g g$ represent opposite stationary right-angular pieces secured to the opposite longitudinal sides of the box a . The horizontal angular portions $h h$ of the pieces $g g$ are each 35 provided with an opening, i , in each of which a lever, k , is pivoted. The inner ends of the levers k are bent at m , and project through the sides of the opening i , and the bent ends of the projecting levers are serrated. The 40 openings i are provided with springs l , the tension of which is exerted against the levers, and forces the ends m of the levers together, to grasp one end of a broken fence-wire.

45 n represents a clamping-lever pivoted to one of the horizontal right-angular pieces h , and provided near its outer end with a notch, o , which engages with a pin, p , secured to the opposite right-angular piece h . The function 50 of the clamping-lever n is to prevent the right-angular pieces $g g$ from spreading in the operation of the machine.

q represents a block arranged to reciprocate on the top face of the box a , over the screw b . The block q is provided with a projection, r , having a central threaded orifice, s , through 55 which the screw b passes. The upper part of the block q is provided with openings t , in which the angular spring-pressed levers u are pivoted. The ends of the angular levers u are serrated to bite one end of the 60 broken wire, placed in a slot, u^2 , in the upper face of the block q . The broken wire projects a short distance beyond the end of the block q , and in the operation of the machine, by turning the crank, one broken end of the 65 wire, secured in the slot u^2 of the block q , is carried forward and passes under and in contact with the other broken end of the wire, held stationary between the serrated jaws of the levers k . The broken ends of the wire, 70 after they have been tightened and all slack has been taken up, are twisted together by hand or by means of a wrench or other tool.

To the bottom of the box a , at its ends, are secured the arms v , to the outer ends of which 75 are pivoted the arms w . The function of the latter is to secure the machine to the wires of a fence when a wire is broken and it is desired to splice it. Each arm w is provided with a series of slots, z , each having an opening, z' , 80 for the insertion of an unbroken wire to support the machine on the fence. If a top wire is broken and needs to be spliced, the arms w are turned down and secured to the lower wires; and if a lower wire is broken, the arms 85 are turned up upon their pivots and secured to the upper wires. When the machine is not in use, the arms w are folded down on each other and on the bottom face of the box a , and are held in place by means of the beveled end 90 of one of the arms, w , passing under the beveled end of a piece, w' , secured to one of the arms w .

Having thus fully described my invention, what I claim as new, and desire to secure by 95 Letters Patent, is—

1. The combination, with the open box a , stationary right-angular pieces $g g$, secured thereto, spring-pressed clamping-levers $k k$, having serrated ends m , and notched lever n , of the 100 reciprocating block q , having slot u^2 , and provided with a projection, r , having a threaded

orifice, *s*, spring-pressed levers *u*, having serrated ends, screw *b*, and beveled pinions *c d*, substantially as shown and described.

2. The combination, with the open box *a*, provided with the arms *v*, of the arms *w*, pivoted to the latter, and provided with the slots *z*, each having an opening, *z'*, substantially as shown and described.
3. The combination, with the box *a*, of the

folding arms *w*, one of which is beveled at its end, and the other arm provided with the beveled piece *w'*, substantially as shown and described.

JONATHAN E. PIERCE.
